ALARM MECHANISM FOR CLOCKS.

1,115,134.

Specification of Letters Patent.

Patented Oct. 27, 1914.

Application filed March 19, 1914. Serial No. 825,864.

To all whom it may concern:

Be it known that I, HOWARD J. TREGANZA, a citizen of the United States, residing in the borough of Brooklyn, county of Kings, city and State of New York, have invented a certain new and useful Improvement in Alarm Mechanism for Clocks, of which the following is a specification.

My invention relates to improvements in alarm mechanism for clocks of the type in which the alarm, after being sounded at a predetermined time, is automatically cut off. Preferably the mechanism is of the kind wherein the alarm may be set so as to sound every twenty-four hours, and I prefer also to utilize the improvements in connection with a switch arrangement of the general character described in my Patent No. 1,088,381 of February 24, 1914, by means of which the alarm may be stopped manually by pressing a convenient button projecting from the clock case.

Alarm mechanisms have heretofore been made in which the alarm will be automatically cut off, but so far as I am aware it has been the practice in the prior art to provide a fixed and definite time during which the alarm will be sounded, say forty seconds, before it is automatically stopped. With my improved mechanism it is possible to adjust the length of time during which the alarm may be sounded, say from seven to fifty seconds, whereby the user may adjust the duration of the alarm to suit his particular requirements. I consider this an important practical advantage, because in the case of a person who may awaken quickly the alarm can be made to sound very briefly without continuing to needlessly ring, as with present arrangements, or without necessitating manually stopping the same if the switch arrangement is used.

My invention relates, therefore, in the first place to mechanism by which the duration of the sounding of the alarm may be adjusted, and in the second place to improved mechanism by which the alarm will be automatically cut off, the latter mechanism being preferably combined with the former, all as I will more fully hereinafter describe and claim.

In order that the invention may be better understood attention is directed to the accompanying drawings forming part of this specification, and in which,

Figure 1 is a longitudinal section of the alarm mechanism of a standard clock embodying my improvements in their preferred form, illustrating in full lines the position of the parts before the alarm is tripped, and in dotted lines the position of the parts after the alarm has sounded and has been stopped by the automatic mechanism; Fig. 2 is a plan view of Fig. 1; Fig. 3 is a detail view showing the parts comprising the automatic stop, illustrating in full lines the position of the parts while the alarm is sounding, and in dotted lines the position of the parts after the automatic stop mechanism has operated; Fig. 4 is a plan view of the clock illustrating the pointer for determining the sounding time of the alarm; and Fig. 5 is a section on the line 5—5 of Fig. 2.

In the above views corresponding parts are designated by the same reference numerals.

Since the present improvements relate entirely to the alarm side of the mechanism I do not show any of the mechanism comprising the time side, except the gear 1 which trips the alarm in the usual way, and which is rotated by the clock mechanism, preferably once in twenty-four hours. The gear 1 is mounted on the setting shaft 2 so as to rotate thereon, and being also movable longitudinally with respect to the same in the usual way. The setting shaft 2 is mounted in the frame 3—3 and carries the usual knob 4 at the back of the clock case by which the shaft 2 may be turned to any predetermined point and thereby set the alarm. The setting shaft 2 carries the usual stud 5 (see Fig. 5) that enters the notch 6 carried by the trip gear 1, which notch is formed with an inclined or cammed side in the usual way, whereby after the alarm has sounded the further rotation of the gear 1 will cause it to slowly move longitudinally of the shaft 2, so as to return the parts to their operative position for the succeeding sounding of the alarm.

Engaging the hub of the gear 1 is a lever 7, whose lower end is secured to the front plate of the frame, and whose upper portion engages the forward end of an arbor 8 mounted in the frame 3—3 so as to be movable longitudinally therein, and being also capable of a rocking movement in said frame. A spring 9 surrounds the arbor 8

and impels the same forward when the stud 5 enters the notch 6 to trip the alarm.

The alarm mechanism comprises the usual spring 10 and gearing between the same and the pallet wheel 11, with which coöperates the pallet 12 carrying the hammer 13. The oscillating pallet shaft is provided with an arm 14 extending parallel with the front frame and adapted to be engaged by a stud 15 carried by the lever 7, and projecting through the front frame so as to thereby lock the alarm mechanism against movement.

Formed, preferably as a part of the arm 14, is an upright arm 16 which partakes of the oscillating movement of the pallet. Mounted above, and extending parallel with the arm 14 is a locking arm 17 having an inturned end 18 adapted to be brought into engagement behind the arm 16, so as to stop the alarm mechanism. The arm 17 is carried by the arbor 8, as shown, and is provided with an extension 19 engaging one of the frame posts and limiting the upward movement of the arm 17, as shown in Fig. 1. A torsion spring 19^a engages the arbor 8 and thereby holds the arm 17 normally in its upward position. Extending downwardly from the arm 17 is an arm 20, whose lower end carries an inturned pointed finger 21. This latter finger is adapted to coöperate with a spiral groove formed in a plate 22 and carried by the gear 23 of the alarm mechanism, whereby, as said gear rotates, the spiral groove, or snail, will draw the arm 20 downwardly, carrying the arm 17 and inturned end 18 to a position in horizontal alinement with the upper end of the arm 16. This snail is a plane spiral cam. The snail is provided with a central opening 24 whereby, when the finger 21 has progressed the entire length of the spiral groove, it may enter said opening to thereby permit the arm 17 and inturned end 18 to move laterally, to thereby engage the inturned end 18 behind the arm 16 and stop the alarm mechanism. In order to provide for an adjustment of the time during which the alarm shall sound I arrange the mechanism in such a way that the arm 20, on its return movement, will be limited more or less to cause the finger 21 to engage the snail groove more or less toward the central opening 24, thereby determining the number of turns of the snail that may be required to bring the finger 21 into position to enter the opening 24. A convenient arrangement for this purpose is an inclined stop 25, arranged to be engaged with a horizontal portion of the arm 20 on its return movement, and carried by a slotted plate 26 mounted to be moved circumferentially in the clock case, and provided with a finger 27 coöoperating with a scale 28, suitably marked with the words "Long alarm" and

"Short alarm", or any other suitable designation. By shifting the position of the pointer 27 the stop 25 will be adjusted, with respect to the horizontal portion of the arm 20, so as to thereby limit more or less the return movement of said arm. In order to provide a suitable switch to manually cut off the alarm I preferably form the arm 17, with an extension 29, with which a spring pressed plunger 30 coöperates, having a finger piece 31 projecting above the clock case.

From the preceding description the operation will be very readily understood. With the parts as shown in full lines in Fig. 2 the stud 5 is being approached by the notch 6, and the alarm is held against operation by the stud 15, engaging above the arm 14. The inturned end 18, which constitutes a locking finger, will be located above the arm 16 and in a vertical plane behind the same, and the finger 21 will be withdrawn from contact with the snail groove, as shown in Fig. 3. When the stud 5 comes opposite the notch 6 by the continued rotation of the gear 1, the latter will be free to move longitudinally on the setting shaft 2, and will be moved longitudinally thereon by the spring 9 on the arbor 8. This will release the finger 15 from the arm 14, and free the pallet so that the alarm will sound. The longitudinal movement of the arbor 8 moves the arm 17 until the finger 21 engages the snail groove, but the inturned end 18 will still be out of vertical alinement with the arm 16. As the snail rotates the finger 21 will be slowly drawn downward, during which time the alarm will sound, until said finger is free to enter the opening 24, whereupon the spring 9 will move the arbor a further step, thereby bringing the inturned end 18 behind the arm 16 so as to automatically stop the alarm. After the alarm has sounded the continued movement of the gear 1 will cause the cam side of the notch 6, engaging the stud 5, to move the gear longitudinally to the position shown in Fig. 2, thereby first engaging the stud 15 above the arm 14, then withdrawing the inturned end 18 from behind the arm 16, and finally forcing the finger 21 clear of the opening 24 so as to permit the spring 19^a to again elevate the arm 17, until it engages the limiting stop 25 which determines the upper movement of the finger 21 and fixes the point at which said finger shall engage the snail groove to thereby regulate the duration of the alarm. If, during the sounding of the alarm it is desired to stop the same, this is done by pressing the finger-piece 31, which depresses the arm 17, causing the finger 21 to ride radially over the snail teeth until it enters the opening 24, and thereby permits the spring 9 to move the arbor 8 and bring the inturned end 18 behind the arm 16.

Having now described my invention, what I claim as new and desire to secure by Letters Patent, is:

1. In an alarm mechanism for clocks, the combination with the alarm mechanism, of mechanism for automatically stopping the alarm, said mechanism employing a plane spiral cam operated by the alarm mechanism; and a finger engaging said cam and moved thereby, substantially as set forth.

2. In an alarm mechanism for clocks, the combination with the alarm mechanism, of mechanism for automatically stopping the alarm, said mechanism employing a plane spiral cam operated by the alarm mechanism; and a finger engaging said cam and moved thereby, and a determining device for adjusting the point at which said finger may engage the cam to thereby regulate the sounding period of the alarm, substantially as set forth.

3. In an alarm mechanism for clocks, the combination with the alarm mechanism employing an oscillating pallet of an arm adapted to be moved so as to stop the pallet, a finger carried by said arm, and a plane spiral cam operated by the alarm mechanism and with which said finger coöperates so as to thereby move the arm into position to stop the pallet, substantially as set forth.

4. In an alarm mechanism for clocks, the combination with the alarm mechanism employing an oscillating pallet, of a pivoted arm carrying a locking finger normally out of vertical and horizontal alinement with the pallet, a plane spiral cam rotated by the alarm mechanism and formed with a central

opening, and a finger coöperating with said cam and carried by said arm whereby the rotation of the cam will move said finger to carry the locking finger into horizontal alinement with the pallet, and the engagement of said finger with said opening will permit the locking finger to be moved into vertical alinement with the pallet to thereby automatically lock the alarm mechanism, substantially as set forth.

5. In an alarm mechanism for clocks the combination with the alarm mechanism employing an oscillating pallet, of a pivoted arm carrying a locking finger normally out of vertical and horizontal alinement with the pallet, a plane spiral cam rotated by the alarm mechanism and formed with a central opening, and a finger coöperating with said cam and carried by said arm whereby the rotation of the snail will move said finger to carry the locking finger into horizontal alinement with the pallet, and the engagement of said finger with said opening will permit the locking finger to be moved into vertical alinement with the pallet to thereby automatically lock the alarm mechanism, and means for determining the point at which said finger shall engage the cam to thereby regulate the alarm period, substantially as set forth.

This specification signed and witnessed this eighteenth day of March, 1914.

HOWARD J. TREGANZA.
